UNITED STATES PATENT OFFICE.

ALEXANDER T. DRYSDALE, OF LOUISVILLE, KENTUCKY.

MOLDING-MACHINE.

No. 888,004.

Specification of Letters Patent.

Patented May 19, 1908.

Application filed November 15, 1906. Serial No. 343,571.

To all whom it may concern:

Be it known that I, ALEXANDER T. DRYSDALE, a citizen of the United States, residing at Louisville, in the county of Jefferson and 5 State of Kentucky, have invented certain new and useful Improvements in Molding-Machines, of which the following is a specification.

The object of my invention is to produce 10 an improved molding machine which shall be compact, easily operated, and capable of producing a uniform compression of the sand.

The accompanying drawings illustrate my 15 invention.

Figure 1 is a central vertical section of my improved machine with the parts in initial position; Figs. 2, 3 and 4, similar views showing the parts in successive positions.

20 In the drawings 10 indicates a pedestal which, at its upper end, supports a hollow casing 11, the upper end 12 of which forms the follow board having a central opening adapted to fit the pattern 13, which pattern 25 is provided with a portion 13' of substantially uniform cross section. Pattern 13 is carried at the upper end of a plunger 14 vertically reciprocable within a cylinder 15 formed in the upper end of pedestal 10. 30 Leading into cylinder 15 is a feed pipe 16 having a suitable three-way controlling valve 16'. At an intermediate point pedestal 10 is provided with an enlargement forming a piston head 17 which fits the interior of a cylinder 18, thus forming, within said cylinder, an upper chamber 19 and a lower chamber 20, the lower end of the cylinder fitting snugly upon the lower cylindrical end of the pedestal 10, as shown. Sleeved upon the upper 40 end of pedestal 10 is a hollow plunger 21 which extends down into chamber 19 of cylinder 18, the upper end of the cylinder 18 fitting the exterior of said hollow plunger snugly. Leading into chamber 20 is a supply pipe 22 having a suitable controlling valve 22' and leading into the chamber 19 is a suitable supply pipe 23 having a controlling valve 23'. The hollow plunger 21 carries a stool 25 at its upper end, said stool being adapted to support a supplemental flask 26. The supplemental flask 26 receives the main flask 27 and the upper end of main flask 27 receives a second supplemental flask 28, the depth of the supplemental flasks being such as to provide for proper compression 55 of the sand, as described later. Pivottally

connected to the cylinder 18 by suitable bars 30 is a pressure head 31 which carries a compression plate 32 adapted to enter the upper end of the supplemental flask 28.

The operation is as follows: With the parts 60 in the positions shown in Fig. 1, the several flasks have been filled with sand and there is a fluid pressure within the lower end of cylinder 15 and within chamber 19, said pressures being sufficient to hold the pattern 13 in its initial position and the stool 25 in its initial position. Fluid pressure is then introduced into chamber 20, said fluid pressure being in excess of the fluid pressure in chamber 19. Thereupon the cylinder 18 is moved 65 downwardly over piston 17 to the position shown in Fig. 2, the compression plate 32 passing down through the supplemental flask 28 until it comes level with the top of the 70 main flask 27. At the same time the cross head 31 comes into engagement with the top of supplemental flask 28. Further fluid pressure within chamber 20 causes the flasks to move downwardly relative to the follow 75 board, which remains stationary, and, the pattern being supported by a fluid pressure less than the fluid pressure exerted in chamber 20, the pattern also yields downwardly and moves down through the follow board 80 until the parts are brought to the positions shown in Fig. 3, where the follow board lies even with the lower end of the main flask 27, the sand being thus compressed immediately 85 adjacent the pattern. Thereupon the fluid pressure is withdrawn from cylinder 15 and the pattern sinks to the position shown in Fig. 4. Thereupon fluid pressure is withdrawn from chamber 20 and introduced into chamber 19, thus driving cylinder 18 and the hollow plunger 21 upward to their initial 90 positions, so that flask 27 with the completed mold therein may be withdrawn, a new flask introduced, the several flasks filled with sand, and the operation repeated.

It will be readily understood that other means may be used to effect the necessary movements of the compression plate, the flasks and the pattern, without departing from my invention.

I claim as my invention:

1. In a molding machine, the combination, with a stationary follow board, of a pattern support and pattern movable relative thereto whereby there is a stripping action 110 between the follow board and pattern, a flask support also movable relative to the follow

board, and a compressor plate arranged to coact with the follow board and movable relative thereto.

2. In a molding machine, a pedestal, said pedestal having a cylinder in its upper end and a piston head intermediate its height, a cylinder sleeved upon said piston head, means for introducing fluid pressure into said cylinder upon each side of the piston head, 10 means for introducing fluid pressure into the pedestal-cylinder, a plunger mounted in said pedestal-cylinder, a tubular plunger sleeved over the piston head, a pattern carried by the plunger, a follow board carried by the pedestal, a flask support carried by the hollow plunger, and a compression plate carried by the movable cylinder, 15 the said movable cylinder carrying means for engaging flasks carried by the flask support, all of said parts being combined and arranged substantially as and for the purpose set forth.

3. In a molding machine, a pedestal and follow board carried thereby, said pedestal having a cylinder in its upper end and a piston head intermediate its height, a cylinder sleeved upon said piston head, means for introducing fluid pressure into said cylinder upon each side of the piston head, means for 20

introducing fluid pressure into the pedestal-cylinder, a plunger mounted in said pedestal-cylinder, a tubular plunger sleeved upon the pedestal and projecting into one end of the cylinder sleeved over the piston head, a pattern carried by the plunger, a follow board carried by the pedestal, a flask support carried by the hollow plunger, and a compression plate carried by the movable cylinder, 25 the said movable cylinder carrying means for engaging flasks carried by the flask support, all of said parts being combined and arranged 30 substantially as and for the purpose set forth.

In witness whereof, I, have hereunto set my hand and seal at Louisville, Kentucky, this ninth day of November, A. D. one thousand 40 nine hundred and six.

ALEXANDER T. DRYSDALE. [L. S.]
